VICTOR J. HULTQUIST, OF ALCOA, TENNESSEE

HANDLING APPARATUS FOR TILE

Application filed July 24, 1928. Serial No. 295,003.

This invention is directed to a handling apparatus for tile or the like wherein the tile immediately succeeding their delivery from the tile forming machine are assembled 5 in a manner to protect their wearing sides and faces during the subsequent drying and burning processes.

In the manufacture of tile or the like, it is well known that an appreciable proportion 10 of such tile are damaged in their wearing sides or faces during the drying and burning processes, with the result that such damaged tile are of secondary grade and constitute no inconsiderable loss to the tile manufacturer. The tile as delivered from the tile 15 making machine are in a semi-plastic or softened condition and incident to their contact one with the other, particularly of the bottom face of one tile with the wearing face 20 of another, the wearing faces of some of the tile will be marred or scored with the result that when dried and burned, such tile are so imperfect as to permit their use only as second grade even if they can be used at all. 25 It is highly important, therefore, that in the handling of the tile following their delivery from the tile making machine, the wearing faces must be protected against the possibility of marring contact from other tile 30 and that this protection should be maintained during the drying and burning processes in order that the wearing faces shall, throughout the completion of the manufacturing process, be absolutely protected and thus 35 maintained in as perfect condition as when delivered from the tile forming machine.

It is, therefore, the principal object of the present invention to provide an apparatus on 40 which the tile, taken from the off-bearing belt of the tile forming machine, either mechanically or automatically, may be grouped in pairs with the wearing face of the tile of each pair in contact and the tile thus protected subsequently delivered for the drying 45 and burning processes.

A further object of the present invention is the provision of means whereby the tile arranged in pairs in the handling apparatus 50 are turned into upright contacting relation 55 to arrange their wearing faces in intimate

contact and held in such position to permit their convenient removal as a unit for delivery to the trays or conveyor by which they are transported for the drying and burning processes.

A further object of the invention is the provision of means for trimming that edge of the tile which is usually more or less ragged as the result of the operation of the tile forming machine, with such trimming automatically perfected as the tile are moved from one position to the other in the handling apparatus.

The invention is illustrated in the accompanying drawings, in which:

Figure 1 is a plan view of the handling apparatus.

Figure 2 is a section on line 2—2 of Figure 1.

Figure 3 is a transverse section on line 3—3 of Figure 1.

Figure 4 is a broken view similar to Figure 2 with the tile shown in elevated or final positions.

Figure 5 is a sectional detail showing the trimming means.

Figure 6 is a perspective view showing the composite hinge member for the tile apparatus, the parts of such member being shown separated.

In the ordinary manufacture of ceramic tile and the like, the tile, following their delivery from the forming machine, are deposited on an off-bearing belt in slightly spaced relation, and ordinarily are taken from the belt by hand and placed in trays or carriers to be transported for the subsequent drying and burning processes. In the handling of the tile from the off-bearing belt, the wearing faces of some of the tile will be marred or scored incident to their delivery into the trays or carriers with the result of producing imperfect tile.

To avoid this objection, the tile handling apparatus of the present invention is arranged adjacent the off-bearing belt and the tile taken from the belt in pairs are arranged on the apparatus and the apparatus operated to cause the tile to be positioned in mating contact with their wearing faces adjacent,

from which position the two tile are removed as a unit and placed on the trays or carriers in proper relation for transportation for drying and burning.

After the tile are positioned in the tile handling apparatus of this invention, they are subsequently handled as a unit and their wearing faces are adequately protected against injury, with the result that a very much larger proportion of perfect tile follow the usual drying and burning processes than has been heretofore possible. Of course, it will be understood that a sufficient number of tile handling apparatus of the present invention will be arranged in relation to the off-bearing belt to permit all tile delivered by said belt to be properly handled.

The tile handling apparatus of the present invention comprises a suitably supported frame including end bars 1 and side bars 2, the latter being preferably in independent longitudinally aligned sections connected by a strip 3 secured to the section by bolts 4, the bolts passing through elongated openings 5 in the strip 3 to permit variable spacing between the meeting ends of the sections of the side bars to adjust the overall length of the frame for the accommodation of tile of different thicknesses. The end bars 1 removably support plates 6 which, as will later appear, have their upper surfaces in the plane of the tile-receiving platen and are designed to be replaced or adjusted when longer platen are to be used.

The respective sections of the side bars 2 remote from the off-bearing belt with which the apparatus is associated are provided with upstanding metallic plates 7 constituting and hereinafter referred to as side gauging strips for the tile, these strips having the additional function of providing for the trimming of the particular edge of the tile as will be later described.

Supported in the inner or adjacent ends of the similar sections of the side bars 2 are pintle rods or shafts 8, said pintle rods being thus arranged in spaced parallel relation transversely of the apparatus. Supported on each of these pintle rods is what may be termed upper and lower hinge bars 9 and 10, the latter cooperating with the pintle rod through a central gudgeon 11 and the former cooperating with the pintle rod through end gudgeons 12 between which the gudgeon 11 is fitted, whereby to permit unit movement of the upper and lower hinge bars on the pintle rod or their independent movement on said rod.

Removably secured to each upper hinge rod 9 and on the relatively outer face thereof is a plate 13 providing an end gauging plate for the tile. The thickness of the lower hinge bar 10 is substantially equal to the combined thickness of the upper hinge bar 9 and the plate 13, so that when the machine is in nor-

mal position and the respective hinge bars are in vertical alignment, the lower edge of the end gauging plate 13 rests squarely upon the upper edge of the lower hinge bar 10 beyond the gudgeon 11 thereon.

A pair of bracket arms 14 are secured to the lower hinge bars 10 with the main links of such arms extending at right angles to such hinge bar toward the adjacent end block 1 of the frame and on a plane above the lower edge of the end gauging plate 13. Removably secured on each pair of the bracket arms is a pallet 15 presenting a smooth even upper surface to receive and support the tile as it is delivered from the off-bearing belt. These pallets are removably connected to the bracket arms and have a dimension substantially corresponding to the space between the side bars and end bar at one side of the end gauging plate 13.

By this arrangement and as particularly noted in Figures 2 and 3, the upper surface of the pallet 15 is above the lower edge of the end gauging bar 13 and is wholly free of direct connection with said end gauging bar while at the same time bearing squarely against said end gauging bar when the parts are in normal inoperative positions.

Each lower end bar 10 carries an operating arm 16 connected at its upper end to the approximate longitudinal edge of the hinge bar and depending from said hinge bar at an inclination toward the remaining hinge bar, the lower terminals of the operating arms being thus arranged slightly at one side of the transverse center of the apparatus. The lower end of each arm 16 is connected through a flexible connector 17 with a treadle 18, the connectors passing over idlers 19 connected to the end bars 1 and over a central double idler 20 supported on the frame.

The movement of each operating bar 16 is opposed by a spring 21 connected to the bar and leading therefrom in a direction opposite that of its connector and terminally connected to the frame bar 1. Thus, the operating bar 16 may be simultaneously operated by the pressure on the treadle and simultaneously returned to normal position by the springs 21 when the pressure on the treadle is released.

Each upper hinge bar 9 is connected on its inner side to an operating arm 22, these arms extending from each hinge bar at a slight downward inclination toward and beyond the transverse center line of the machine and then vertically of the machine to a point slightly above the upper ends of the operating arms 16. As thus arranged, the operating arms 22 of the respective upper hinge bars 9 cross each other at the transverse center of the apparatus and are, of course, relatively offset to avoid interference in movement.

The lower ends of the operating arms 22

are connected by flexible connector 23 to weights 24 which slightly overbalance the weight of the upper hinge bar and the connected end gauging plate 13. The connectors 23 preferably pass over idlers on the shafts 19.

In the use of the apparatus, assuming the parts in normal position as illustrated in full lines in Figure 2, two tile or other like article are removed from the off-bearing belt and deposited one on each of the platen 15, the tile being positioned against the side gauging plates 7 and end gauging plates 13, with their wearing sides or faces uppermost. The treadle 18 is then depressed and, through the connectors 17 and operating arms 16, the respective upper and lower hinge bars 9 and 10 respectively are moved as a unit on the pindle rods 8. In this movement, the pallets 15 carrying the tile are swung upwardly into a vertical position, the tile being then supported on their edges and on the end gauging plates 13, as shown more particularly in Figure 4.

On releasing pressure on the treadle, the springs 21 act through the operating bars 16 to return the lower hinge bars 10 and pallets 15 to their normal or inoperative positions, leaving the tile standing vertically on the end gauging plates 13. The weights 24 are insufficient to overcome the additional weight of the tile on the end gauging plates 13 and hence the end gauging plates 13 remain as supports for the tile while the tile are in this upright position.

With the spacing of the end bars 2 arranged to accommodate the thickness of the particular tile or article being handled, it will be understood that when the tile are turned upwardly in the manner described, their wearing faces will be brought into contact and the tile thus held as a unit with such wearing faces completely covered and protected one by the other. The two tile thus associated are removed as a unit from the apparatus and delivered to the trays or carriers for the further processes of drying and burning. Immediately the tile are removed from the end gauging plates 13, the weights 24 act to return the end gauging plates to their normal positions, that is, in proper relation to the platen to receive the next pair of tile.

The tile, as delivered from the tile forming machine, frequently present a ragged edge, and it is desirable that this edge be removed in order to permit a more perfect setting of the tile. To secure this result, the side gauging plates 7 are formed with longitudinally extending openings 25 to the upper edges of which are secured trimmers 26, preferably in the form of sharpened blades or the like. As the tile are turned upwardly through the movement of the platen, it is apparent that the edges in contact with

the side gauging plates 7 will be moved past the trimmer 26 with the effect to remove the ragged edge or small projections from the semi-plastic tile during the operation of moving the tile into the desired position for handling.

The apparatus as a whole lends itself to convenient adjustment for the handling of articles, such as tile or the like, of different sizes, particularly in the transverse and end-wise adjustment described and in the removable connection of the side and end gauging plates 7 and 13 and of the platen 15, for by appropriate adjustment of these parts, it is apparent that tile of different surface area or thickness may be readily and properly accommodated in the apparatus. That is to say, the distance between the platen when upturned must snugly accommodate two tile and this distance may be varied by appropriate spacing of the pindle rods 8 and this appropriate spacing is obviously secured by the corresponding relative adjustment of the sections 2 of the side bars. Where longer tile or articles are to be used and will be accommodated on the platen, the plates 6 may be removed to permit the use of platen of greater length, though obviously if desired the plates 6 may be adjustably connected in position so that they may be readily adjusted to accommodate platens of different lengths.

The important feature of the present apparatus is the provision of means whereby the tile, with minimum handling, are arranged in pairs with the wearing faces of the respective tile in contact and the pair of tile so relatively disposed that they may be subsequently handled as a unit without any exposure whatever of the wearing faces. Thus, the wearing faces are protected against being marred or scored and will, so far as this liability is concerned, be maintained in perfect condition with the result of a greatly increased proportion of perfect tile as compared with the former methods of handling.

Of course, it is to be understood that while reference is made more or less specifically herein to tile, the apparatus may, with equal facility and small mechanical change, be adapted for the handling of other ceramic articles in which it is desired to protect a particular face or portion against damage during the transfer from the off-bearing belt to the trays or carriers for subsequent treatment.

Furthermore, it is of course to be understood that any and all parts of the apparatus may be in any desired relative proportion suitable for the particular work and may be constructed of any appropriate material which may be found of service. In this connection, it is to be noted that the side and end gauging plates 7 and 13 and also the platen are preferably of metal to insure a

true and even surface to avoid any possible distortion of the semi-plastic article while being handled in the apparatus.

What is claimed to be new is:

- 5 1. A handling apparatus for tile or the like, including supports for adjacent tile on which the tile are to be arranged with their wearing faces uppermost each support comprising a platen and guage hinged together 70
10 to receive the end and side of a tile, means for moving the supports relatively toward each other to move the tile carried thereby to a position to cause their wearing faces to contact, means for returning the platens to normal position while the tile are supported on the gauges, and means for returning the gauges to normal position when the tile are removed. 75
- 15 2. A handling apparatus for tile, including supports for the tile made up of independently movable sections and mounted for pivotal movement to engage the ends and sides of adjacent tile, means for normally maintaining the supports in substantially the same horizontal plane, means for moving the supports into a vertical plane to cause the tile carried by the supports to be moved into contact while on the supports, and means associated with the supports for retaining the 80
20 tile in vertical position when one section of both such supports is returned to normal horizontal position. 85
- 25 3. A tile handling apparatus, including a frame, sectional receiving supports for engaging the ends and sides of adjacent tile, means for pivoting the adjacent ends of the supports to the frame, means for normally holding the supports in substantially the same horizontal plane, and means for simultaneously moving the supports into spaced 90
30 parallel vertical planes to thereby clamp the tile carried by the supports between the latter with the tile surfaces in contact, and means associated with and forming part of 95
35 the supports to retain the tile in vertical position when one section of each support is returned to normal horizontal position. 100
- 40 4. A tile handling apparatus, including a pair of tile-receiving supports mounted for swinging movement, pivotally mounted end gauges at the ends of the supports against which the tile are positioned when on the supports, means for simultaneously moving the tile supports and their end gauges to position the tile carried by the supports in face 105
45 contacting relation, means for causing the supports to return to normal position while the gauges remain in operative position with reference to the tile thereon to support the 110
50 tile in vertical position, and means for returning the end gauges to normal position when the tile are removed. 115
- 55 5. A tile handling apparatus, including tile-receiving supports mounted for swinging movement, said supports including piv- 120
60 ing movement, 125
65
- oted end gauges against which the tile are positioned when on the supports, means for moving the tile supports and their end gauges to position the tile carried by the supports in face contacting relation, means for causing the supports to return to normal position while the end gauges remain in operative position to hold the tile in vertical position, and means for returning the end gauges to normal position following the removal of the tile therefrom. 70
6. A tile handling apparatus, including tile-receiving supports arranged in substantially the same horizontal plane and mounted for swinging movement, means for simultaneously moving the supports into substantially vertical position to cause the tile carried thereby to be moved into contact, end gauges for the tile pivoted to the supports and moving with the tile in the movement of the supports, means for automatically returning the supports to normal position following the positioning of the tile in contact, said end gauges serving to carry the tile following the return movement of the supports, and means for returning the end gauges into normal relation with the supports following the removal of the tile therefrom. 80
7. A tile handling apparatus comprising a pair of pivotally mounted supports, each support including a tile-carrying platen and a hinged end gauge mechanism for operating said supports to move the tile carried thereby into face contact, mechanism for returning the tile carrying platens to normal position following the contacting relation of the tile, and mechanism for returning the gauges to normal position following the removal of the tile from the apparatus. 90
8. A tile handling apparatus, comprising tile supports including platen and end gauges, pintle rods on which the platen and end gauges are supported for independent movement, means for moving the platen and end gauges as a unit to position the carried tile in face contact, and means for returning the platen to normal tile-receiving position while permitting the end gauges to remain in operative position to support the tile. 100
9. A tile handling apparatus, comprising tile supports including platen and end gauges, pintle rods on which the platen and end gauges are supported for independent movement, means for moving the platen and end gauges as a unit to position the carried tile in face contact, means for returning the platen to normal tile-receiving position while permitting the end gauges to remain in operative position to support the tile, and means whereby the pintle rods may be relatively adjusted to accommodate tile of different thicknesses. 110
10. A tile handling apparatus, comprising a frame including side bars made up of relatively adjustable sections, tile supporting 120
125

means mounted for pivotal movement on the similar sections of each side bar, said tile-supporting means including platen and end gauges, manually operable means for moving the platen and end gauges as a unit from a normal to an operative position to arrange the tile in face contact, means for automatically returning the platen to a normal position following the contacting relation of the tile, and means for thereafter returning the end gauges to normal position after the vertically disposed tile have been removed and the platens returned to their normal position.

11. A tile handling apparatus, comprising a frame including side bars made up of relatively adjustable sections, tile supporting means mounted for pivotal movement on the similar sections of each side bar, said tile-supporting means including platen and end gauges, means for mounting the platen and gauges to be independently operated when returning the supports to normal position, manually operable means for moving the platen and end gauges as a unit from a normal to an operative position to arrange the tile in face contact, means for automatically returning the platen to a normal position following the contacting relation of the tile, and means independently of the before mentioned automatic means for automatically returning the end gauges to normal position following the removal of the tile from the apparatus, and after the platens have returned to their normal position.

12. A tile handling apparatus, comprising tile-supporting means including an upper hinge bar, a lower hinge bar, means for pivotally supporting the hinge bars for simultaneous or independent movement, a platen carried by the lower hinge bar, an end gauge carried by the upper hinge bar, manual means for operating the hinge bars simultaneously to move the platen and end gauge from a normal to an operative position as a unit, and means for independently returning the platen and end gauge from an operative to a normal position.

13. A tile handling apparatus, including relatively adjustable frame bars, pintle rods carried by the frame bars and adjustable relative to each other through the adjustment of the frame bars, a lower hinge bar mounted on each pintle rod, an upper hinge bar mounted on each pintle rod, a platen carried by the lower hinge bar, an end gauge carried by the upper hinge bar, means for moving the upper and lower hinge bars as a unit from a normal to an operative position, springs for returning the lower hinge bars and platen from an operative to a normal position, and weights for independently returning the upper hinge bars and end gauges from an operative to a normal position.

14. A tile handling apparatus, comprising supports normally arranged in substantially

the same horizontal plane and each support including a platen and a hinged end gauge and each support adapted to receive the end and side of a tile, means for operating the supports to move the tile while carried by the supports into a vertical position with their wearing faces in contact, and means to return the platens to normal position while the tile are supported on the gauges following contacting relation of the tile to thereby present the tile for unit handling free of obstruction to their removal from the apparatus in this relation.

15. A tile handling apparatus, including two-part pivotally mounted supports normally arranged in substantially the same horizontal plane and each support including a hinged end gauge, and each support adapted to receive the end and side of a tile, means for operating the supports to move the tile while carried by the supports into a vertical position with their wearing faces in contact, and means for returning one part of each of the supports to normal position after the tile are in vertical position, and means for thereafter returning the gauges to normal position after the tile are removed.

In testimony whereof I affix my signature.
